UNITED STATES PATENT OFFICE

129,900

DESIGN FOR A TEXTILE FABRIC OR SIMILAR ARTICLE

Gladys E. Eisenhardt, New York, N. Y., assignor to Cohn-Hall-Marx Co., New York, N. Y.

Application July 11, 1941, Serial No. 102,015

Term of patent 3½ years

To all whom it may concern:

Be it known that I, Gladys E. Eisenhardt, a citizen of the United States of America, residing at 22 East 38th Street, New York, New York, have invented a new, original, and ornamental Design for a Textile Fabric or Similar Article, of which the following is a specification, reference being had to the accompanying drawing, forming a part thereof.

The figure is a plan view of a piece of textile fabric, the complete width of which is shown between the full lines and a unit of the same is contained between the dot and dash lines, the same being repeated in regular succession over the entire fabric.

I claim:

The ornamental design for a textile fabric or similar article, as shown and described.

GLADYS E. EISENHARDT.
